INVENTOR
Richard Morris
BY
Adam E. Fisher
ATTORNEY

UNITED STATES PATENT OFFICE.

RICHARD MORRIS, OF GWINN, MICHIGAN.

BED.

1,427,618.

Specification of Letters Patent. Patented Aug. 29, 1922.

Application filed May 21, 1921. Serial No. 471,409.

To all whom it may concern:

Be it known that I, RICHARD MORRIS, a citizen of the United States, residing in the city of Gwinn and State of Michigan, have 5 invented new and useful Improvements in Beds, of which the following is a specification, reference being had to the accompanying drawings.

This invention pertains to beds, and more 10 particularly to hospital beds, and the object is to provide in a simple and practical form of construction, an adjustable hospital bed, with means for readily elevating the head of the bed relative to the foot, or vice versa.

15 In the drawings—

Figure 1 is a perspective view of the bed, showing the head elevated;

Figure 2 is a similar view of the frame of the bed, the spring mattress being removed.

20 Figure 3 is a detail view of the elevator block.

The invention consists of the combination of an ordinary bed frame 1, provided with triangular and demountable elevator blocks 25 2 having retaining notches 3 cut along their long sides, and adapted to be secured to the frame at either the head or foot by means of set screws 4, the notched sides being turned upward. Aligned holes 5 are cut through 30 the side bars 6 of the spring frame 7, at each end, to receive the cross rods 8, and similar holes 9 are cut in the side bars 10 of the bed frame 1, to receive said cross rods 8 when the spring frame is adjusted to level position.

35 To adjust the spring frame 7 to level position, the blocks 2 are all removed, and the cross rods 8 are inserted through a pair of the holes 5 and 9 in the side bars 6 and 10 of the spring frame 7 and bed frame 1, respec-

tively. To adjust either the head or foot of 40 the spring frame 7 to an inclined position, the blocks 2 are mounted on the frame 1, at the head or foot as desired, and the cross rod 8 at that end is withdrawn from the holes 9 in the side bars 10 of the frame 1, 45 and from the holes 5 of the spring frame 7, after which the ends of this rod are positioned in any pair of the notches 3 on the blocks 2, and the end of the spring frame 7 is placed on top of the rod 8, thus holding 50 that end in elevated position. End brackets 11 on the spring frame 7 prevent any mattress placed on the spring frame from sliding off when the frame is inclined.

While I have herein described a certain 55 specific method of constructing and assembling the elements of my invention, it is understood same may be varied in minor details, not departing from the spirit of my invention, as defined in the appended claim. 60

I claim:

An adjustable hospital bed, comprising a bed frame and a spring frame, both having transversely aligned holes at each end; triangular and notched elevator blocks adapted 65 to be secured to the top sides of the side bars of the bed frame at the head or foot; and two cross rods adapted to lockingly pass through the holes in the two frames, or to be withdrawn from engagement with the holes 70 in the side bars of the bed frame and positioned in the notches of the triangular blocks.

RICHARD MORRIS.
